Inventor,
STEPHEN H. EMMENS,
By his attorney
L. E. Smith.

UNITED STATES PATENT OFFICE.

STEPHEN H. EMMENS, OF LONDON, ENGLAND.

GUN AND PROJECTILE FOR THE SAME.

SPECIFICATION forming part of Letters Patent No. 398,595, dated February 26, 1889.

Application filed May 1, 1888. Serial No. 272,469. (No model.)

To all whom it may concern:

Be it known that I, STEPHEN HENRY EMMENS, a subject of the Queen of Great Britain and Ireland, and a resident of London, England, temporarily residing at Harrison, in the State of New York, have invented a new and useful Improvement in Fire-Arms, of which the following is a specification.

The primary objects of this invention are to simplify the action of breech-loading firearms and to augment the efficiency of smooth-bores, which objects I accomplish mainly by dispensing with the ordinary cartridge-shells, which have to be ejected from the piece after each discharge.

The invention consists in certain novel combinations of parts, hereinafter set forth and claimed.

A sheet of drawings accompanies this specification as part thereof. Figure 1 of these drawings represents a longitudinal section of a pistol with its breech open. Fig. 1^x represents a side view of the front end of the pistol with its breech closed. Fig. 2 represents a longitudinal section of the pistol with breech closed and ready for firing, showing a sectional view of the projectile within the barrel. Fig. 3 is an end view of the pistol, showing its breech end. Fig. 3^x represents a cross-section on the line x x, Fig. 1. Fig. 4 is a top view of the pistol as seen in Fig. 2. Figs. 5 and 6 are perspective views of the projectile before and after its discharge.

Like letters of reference indicate corresponding parts in the several figures.

The projectile forming part of this invention is composed of a head, A, which may be of lead or other metal, and a tube, B, which may be cut from drawn metal tubing of suitable weight and diameter. One end of the tube is provided with an internal screw-thread, and the head A is tightly screwed into the same. The other end of the tube, hereinafter termed its "rear end," is chambered or enlarged internally for about one-sixteenth of an inch from its extremity, and the wall of the chambered portion is slightly expanded to render the rear end of the projectile originally flaring in form, as shown in Figs. 2 and 5. The tube is loaded with gunpowder or any other suitable explosive up to the commencement of the chamber, and the charge

is then completed by a thin layer or disk, d, of any suitable detonating explosive, which rests on the shoulder of the chamber, as shown in Fig. 2.

The barrel B' of the fire-arm proper is a straight cylindrical tube of metal, having the inner angle of its rear end chamfered to form a seat, c, for said flaring rear end of the projectile. The barrel is furnished externally near its rear end with two diametrically-opposed pins or studs, b, and slides within an outer tube, C', which is provided with bayonet-joint slots j in its respective sides to accommodate and coat with said studs on the barrel. An opening, o, in the top of said tube C' provides for the insertion of the projectile when the barrel is pulled forward, as shown in Figs. 1 and 3. When the barrel is forced backward to its rear position, (represented in Figs. 1^x, 2, and 4,) said studs come opposite the locking ends of said bayonet-slots, and a slight twist of the barrel brings said studs into said locking ends, as shown in Fig. 1^x. In this position of the barrel the projectile is clamped against an end abutment, E, formed within said tube C' near its rear end, and provided with a small hole, through which the firing-pin F may be projected. Said tube C' is extended behind said abutment E to form a guide-chamber, within which a piston, D, works between a pair of spiral springs, S S². This piston carries the firing-pin F, around which one of said springs is conveniently placed. The other spring, S, surrounds a flat stem, G, connecting said piston D with a cocking-knob, H. A hollow plug, I, behind said tube C' incloses said spring S, the interior of the plug forming a continuation of said guide-chamber within the rear end of the tube C'. The rear end of said plug I is closed, except a hole through which said stem G works back and forth. Behind this closed end a vertical chamber is formed in a projecting upper portion of the plug, and within this vertical chamber a spiral spring, S³, is compressed by a piston, K, composed of a pair of small disks rigidly united by a central stem, which latter extends through a longitudinal slot formed in said stem G and knob H, as indicated by dotted lines in Fig. 1. When the piece is "cocked" by pulling said knob H, the upper disk of said piston K descends in front of the

knob, as shown in Fig. 2, and prevents the premature or accidental projection of the firing-pin.

For discharging the piece, a disengaging-lever, L, is pivoted below said tube C' and plug I. In the example said lever is in the form of a bell-crank with a relatively long arm, the extremity of which is upturned to engage with the piston K, and with its other and shorter arm coupled to the loosely-sliding stem of a trigger-button, M.

A touch on the button M brings the lever L into contact with the lower disk of the stop-piston K, as shown in dotted lines in Fig. 2. A slight pressure on the button then lifts the piston against the pressure of the spring S², so as to disengage its upper disk from the knob H, whereupon the main spring S projects the piston D and therewith the firing-pin F, causing the latter to penetrate or to strike and explode the detonating-disk d, which explodes the charge C within the projectile. The spring S² in front of the piston D becomes compressed owing to the momentum of the piston, so as to permit the projection of the firing-pin. Its recoil partly retracts the firing-pin, the point of which is normally masked by the abutment E, owing to the reaction of said spring S².

A "stock-tube," T, is internally screw-threaded, and tube C' and plug I are screwed into its respective ends. A pair of frame-plates, U, project downward from the stock-tube, and to and between these the cheeks and filling of the stock are secured in customary manner.

It will be understood that the form and dimensions of the weapon and its stock may be varied from those suitable for a pocket-pistol up to those suitable for a powerful shoulder arm.

The smooth-bore barrel B' avoids the waste of power caused by rifling, while the tube B causes the propelling-gases to rush from the projectile to the breech instead of vice versa, so that there is no loss by windage. Moreover, the great comparative length of the projectile, the facility with which it may be centered by properly adjusting the weight of the head and the tube, and the heavy charge of powder that may be safely used all contribute to the great range and accuracy obtainable by the use of fire-arms constructed in accordance with my invention.

Having thus described my said improvement in fire-arms, I claim as my invention and desire to patent under this specification—

1. The combination, substantially as herein-before specified, of a projectile composed of a head and a rearwardly-projecting open-ended tube, which latter contains the charge and is formed with an expanded rear end, and a fire-arm having the rear end of its barrel open and internally chamfered to receive said expanded end of the projectile and having an abutment 65 behind the bore of the barrel, for the purposes set forth.

2. The within-described projectile, composed of a head and a rearwardly-projecting open-ended tube having a chambered and expanded rear end, which tube and its chamber contain the charge and a disk of fulminate, in combination with a fire-arm having the rear end of its barrel open and internally chamfered to receive said expanded end of the projectile, and having an abutment 70 behind the bore, and a firing-pin projected through a hole in said abutment to explode the fulminate, substantially as hereinbefore specified.

3. The combination, substantially as herein-before specified, of a projectile composed of a head and a rearwardly-projecting tube, the latter having its rear end chambered and expanded, a sliding smooth-bore barrel having its rear end internally chamfered and provided externally with bayonet-joint studs, an outer tube having bayonet-joint slots and a projectile admitting opening, and provided with an internal abutment behind the bore of the barrel, a piston behind said abutment 85 provided on its respective sides with a firing-pin and a stem, and a pair of spiral springs on the respective sides of said piston, for the purposes set forth.

4. In combination with the spring-projected piston carrying the firing-pin and having on its back a flat stem which is slotted and provided with a terminal cocking-knob, a spring-projected stop-piston at right angles thereto, having a stem which passes through said slotted stem, and a disk which coacts directly with said knob, and a disengaging-lever acting on said stop-piston to fire the piece, substantially as hereinbefore specified.
